(57) **CLAIM**

The ornamental design for a warning light, as shown and described.

DESCRIPTION

FIG. 1 is a first perspective view of a warning light showing my new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top plan view of thereof; and,

FIG. 8 is a bottom plan view thereof.

The broken lines in the drawings depict portions of the warning light that form no part of the claimed design.
